US00D944332S

(12) **United States Design Patent** (10) Patent No.: **US D944,332 S**
Yu (45) Date of Patent: **** Feb. 22, 2022**

(54) **TOY**

(71) Applicant: **Qingfeng Yu**, Guangdong (CN)

(72) Inventor: **Qingfeng Yu**, Guangdong (CN)

(**) Term: **15 Years**

(21) Appl. No.: **29/769,031**

(22) Filed: **Feb. 3, 2021**

(51) LOC (13) Cl. **21-01**

(52) U.S. Cl.

USPC **D21/468**; D21/475; D21/338

(58) **Field of Classification Search**
